HAND-COMPOSED MATRIX IN TYPOGRAPHICAL LINE-CASTING MACHINES

William Edgar Aynge, Upper Sydenham, London, England, assignor, by mesne assignments, to Mergenthaler Linotype Company, Brooklyn, N. Y., a corporation of New York

Application November 1, 1935, Serial No. 47,740
In Great Britain November 8, 1934

6 Claims. (Cl. 199—49)

This invention relates to the use of hand-composed matrices in typographical line casting machines such as those known commercially under the registered trade-mark "Linotype", in 5 the normal operation of which circulating matrices stored in a magazine are released therefrom by the operation of the keyboard and assembled in order of composition in a so-called assembler elevator from which the composed line is subsequently transferred to the casting mechanism.

It is sometimes desired to cast a few lines from a font of matrices not at the time carried in the machine or from matrices which are too large, or otherwise not intended for machine composition. In such cases it is usual for the operator to set up the line of matrices in the assembler elevator by hand. It has, however, been proposed to adapt machines for the frequent use of matrices not stored in the magazines by providing special forms of hand-sticks which, after the matrices are composed therein, are either placed in the so-called first elevator by which the matrices are presented to the mould while still in the hand-stick, or are placed in the machine 20 in a position enabling the line of matrices to be transferred by hand from the stick into the first elevator. These arrangements necessitate alterations or additions to the machine parts to enable the hand-sticks to be used. Moreover, after 25 casting the hand-composed matrices must be removed from the machine by hand.

The present invention contemplates a method of introducing a complete line of hand-composed matrices into the assembler elevator, which demands no change in the form of any member of the machine and permits the line of matrices to be controlled by the normal operations of the machine, from its introduction into the assembler elevator to the first stage of the distribution.

40 In carrying out the invention a line of matrices is first composed in a special hand-stick having means for releasably clamping the line thereon, the hand-stick is positioned against the assembler elevator, the line clamp released to permit the matrices to fall by gravity into the assembler elevator, and thereafter the line is sent away for casting in the usual manner. After casting, the second elevator, by which matrices are normally conveyed to the distributing mechanism of the 45 machine, is stopped at an intermediate stage, as is usual for the removal of hand-composed matrices, and the hand-stick is applied to the line then suspended from the second elevator head and the clamping device actuated to secure the 50 line on the stick, so that by manipulation of the

stick the line can be removed as a whole from the elevator head without handling the matrices.

The invention is hereinafter more particularly described with reference to the accompanying drawings in which:—

5 Figure 1 is a front elevation of one constructional form of hand-stick according to the invention;

10 Figure 2 is a plan of the hand-stick illustrated in Figure 1;

Figure 3 is an end elevation of the same as viewed from the right of Figure 1;

15 Figure 4 is a front elevation of a portion of the assembling mechanism of a composing machine showing the method of applying the hand-stick thereto;

20 Figure 5 is a perspective view of a portion of the second elevator of the machine illustrating the use of the hand-stick in removing the matrices therefrom;

Figure 6 is a front elevation similar to Figure 1 of an alternative constructional form of hand-stick;

25 Figure 7 is a sectional view taken on the line 1—1 of Figure 6, and

Figure 8 is an end elevation, similar to Figure 3, of the said alternative construction.

Throughout the several figures of the drawings like reference numerals are used to indicate like or corresponding parts.

30 The hand-stick illustrated in detail in Figures 1 to 3 may be mainly of the usual form comprising a matrix supporting shelf 1 on which the matrices are assembled between a normally fixed line abutment 2 and an adjustable abutment 3 which is carried by a slide 4 embracing a notched flange 5 extending upwardly from the front of the shelf 1 along one side thereof. This slide 35 also carries a spring-controlled catch 6 normally engaging one or other of the notches 7 of the flange 5 to determine the position in which the adjustable abutment 3 is set according to the length of line to be composed, the limit of such length being determined by a stop 19 engaging a notch 20 in the horizontal flange of the abutment. The shelf is preferably provided with a scale marked off in ems, as shown, to assist in 40 positioning the abutment 3.

45 A convenient form of the clamping means required for carrying out the present invention, 50 may be provided by so mounting the normally fixed abutment 2 in relation to the hand-stick that it may be moved inwardly to exert a clamping pressure on the line when desired.

55 According to the constructional form illustrat-

ed, the abutment 2 has a lateral flange 8 slidably fitted within a dovetail slot 9 formed in the shelf 1, and the flange 8 is secured, as by screws 10, to a plate 11 at the rear of the shelf 1, which 5 plate is formed with a rearwardly projecting lug 12. A plate 13, secured by rivets 13a to the underside of the shelf, is formed with a corresponding rearwardly projecting lug 14. Studs 15 extending inwardly from the lugs 12, 14, serve 10 to support a spring 16 which retains the abutment 2 in its normal fixed position by holding the plate 11 against a fixed stop 17 at the rear of the shelf 1 which engages a notch 18 in the plate. The lugs 12, 14, thus form a finger and 15 thumb grip by means of which the stick may be handled, and the line clamped and released when desired.

In Figures 1 and 2 the hand-stick is shown 20 with the adjustable abutment 3 set for the composition of a line of 24 ems in length, and the abutment 2 in the normal position in which it is retained by the spring 16.

The use of the hand-stick just described for 25 the insertion of a composed matrix line into the machine, is illustrated in Figure 4. The assembling mechanism there represented is of known form, comprising an assembler elevator 21 to which machine composed matrices are normally delivered by a rotating star wheel 22, and which 30 is vertically movable in guides 24, 25 on the fixed front plate 26 of the machine for delivery of the line to the casting mechanism. The assembler elevator has the known hinged front gate 23 and a front wall 27, forming with the rear wall (not shown) a channel in which the matrices are supported by their ears on rails projecting inwardly from said front and back walls.

When the composition of the line in the hand- 40 stick has been completed, the lugs 12, 14 are gripped and the abutment 2 thereby actuated to clamp the line against the abutment 3. With the matrices thus secured against displacement, the hand-stick is inserted and placed against the assembler elevator with the flange 5 uppermost 45 and the edge 28 of the shelf 1 resting on the top surface of the assembler elevator front wall 27, the hinged front gate 23 having been previously lowered to the position indicated in Figure 4. The line clamping abutment 2 is then released 50 and moves outwardly under the action of the spring 16, thus permitting the matrices to fall by gravity into the channel of the assembler elevator 21 to be supported therein in the usual manner by the rails above mentioned. The removal of the hand-stick and the return of the 55 gate 23 to its normal position then leaves the line in the assembler elevator ready for the ascent of the latter to transfer the line to the casting mechanism, according to the usual cycle of operations of the machine.

It should here be noted that the abutment 2 is recessed, as indicated at 29 in Figure 3, to provide clearance for the star wheel 22 when the 60 stick is held in position against the assembler, as above described.

The method of using the hand-stick for the removal of the line from the machine after casting, will now be described with reference to 70 Figure 5. In the normal operation of the machine, the second elevator 30 serves in known manner to convey a matrix line 32, suspended on the carrier bar 31, from the casting mechanism to the distributing mechanism by which the 75 matrices are restored to the magazines of the

machine. In the case of lines of hand composed matrices, however, it is customary to arrest the second elevator 30 in an intermediate position between the casting and distributing mechanisms, and to remove the matrices from the carrier bar 31 by hand, which, particularly when a number of slugs have been cast from a single line, necessitates waiting until the matrices are sufficiently cool to handle. The inconvenience of this procedure is avoided according to the 10 present invention by the use of the hand-stick for the removal of the line from the second elevator in the arrested position of the latter. For this operation the hand-stick is used, as shown in Figure 5, in a position the reverse of that appropriate to the insertion of the matrix line into the assembler, that is to say, the hand-stick is held with its flange 5 lowermost and is applied to the matrices suspended from the carrier bar 31. The lugs 12, 14, are then gripped to clamp 20 the matrix line between the abutments 2, 3 and the stick moved endwise to slide the line as a whole off the carrier bar 31.

The shelf 1 of the above described hand-stick has a plane surface on which the ears of the 25 matrices rest and the spacing of the line may be accomplished by the use of quads. The invention, however, contemplates the adaptation of the hand-stick for the use in the composed line 30 of spacebands of known form having ears which, when the spacebands are assembled in the composed line, extend beyond the plane of the ears of the matrices, and for such adaptation of the hand-stick the shelf may be provided with grooves and/or rails for supporting the matrices and 35 spacebands during the composition of the line, and means, preferably actuated by the application of the stick to the assembler, whereby the elements of the line are disengaged from such grooves or rails and permitted to fall by gravity 40 into the assembler.

An example of a hand-stick, mainly of the same form as that hereinbefore described, but modified with the just mentioned requirements in view, is illustrated in Figures 6 to 8. In these 45 figures, the parts which are identical, or substantially so, with parts hereinbefore described are identified by the same reference numerals as those appertaining to the respective parts in Figures 1 to 5, and need not be further described. 50

In the said modified form of hand-stick, there is provided a movable assembling shelf 33, arranged to overlie the shelf 1 and yieldingly supported in spaced relation thereto by studs 34 passing through holes in the shelf 1 and encircled 55 by springs 35. The line clamping abutment 2 is carried by the shelf 1 as above described, and extends upwardly through a recess 36 at the respective end of the shelf 33 with its edges 37 (Figure 8) overlying the said shelf at each side of 60 the recess, the latter being long enough to permit the line clamping movement of the abutment. The abutment 3 overlies the shelf 33 and is supported on the flange 5 by the slide 4, the stop 19 which determines the extreme position of this 65 abutment being in this instance passed through a hole in the shelf 33 to permit of its engagement with the notch 28 on the abutment 3.

The shelf 33 is narrower than the shelf 1 so 70 that its inner edge is spaced apart from the inner edge of the flange 5 a distance corresponding to the width of the ears on the spacebands, the said ears being thus accommodated in the gap 39 between the shelf and flange when the spacebands are assembled in line, while the ears of the mat- 75

rices, which are longer than those of the spacebands, rest on the shelf 33 during composition.

The ends of the shelf 33 are formed with rearwardly and laterally offset flanges 38 extending beyond the ends of the shelf 1, which, when the hand-stick is applied to the assembler, come into engagement with relatively fixed parts such as the intermediate channel plate 41 and assembler cover plate 42 (Figure 4).

It will now be understood that, after the matrices and spacebands have been composed in the stick, with the respective ears of the spacebands projecting into the gap 39, and with the aid of an adjustable or removable support (not shown) for the lower ends of the spacebands, the line may be clamped as before described and applied to the assembler in such a manner that the spacebands are passed into the assembler channel from above and the hand-stick lowered to a position corresponding with that represented in Figure 4. Inward pressure on the stick in this position, the flanges 38 being held against inward movement, effects the disengagement of the shelf 33 from the spaceband ears, so that when the clamping pressure on the lugs 12, 14 is released, the matrices and spacebands drop by gravity to their correct position in the assembler. To ensure the release of the spacebands from the shelf 33, a rail or filler piece 40 may be provided, which fills the gap 39 between the shelf 33 and flange 5 when the shelves 33 and 1 are brought together against the action of the spring 16.

The constructional forms of hand-stick above described and illustrated on the drawings are chosen as convenient examples, and it is to be understood that variations and modifications may be made therein without departing from the invention.

Having described my invention, I declare that what I claim and desire to secure by Letters Patent is:—

1. A hand-stick comprising in combination a matrix supporting shelf, an adjustable line abutment, a normally fixed line abutment, and manually operable means adapted to actuate said normally fixed abutment to clamp a composed line.

2. A hand-stick comprising in combination a matrix supporting shelf, an adjustable line abutment, a second line abutment yieldingly held in a fixed position relatively to the shelf and man-

ually operable means adapted to actuate said second abutment to exert a clamping pressure on a composed line between the two abutments.

3. A hand-stick comprising in combination a matrix supporting shelf, an adjustable line abutment, a normally fixed line abutment, a lateral flange on said normally fixed line abutment slidably fitted within a dovetail slot in the shelf, a rearwardly projecting lug rigidly connected with said flange, a second rearwardly projecting lug rigidly secured to the underside of the shelf and a spring acting between said lugs to retain the flange and its associated abutment in the normal fixed position.

4. A hand-stick adapted to be applied to the assembler elevator of a matrix-composing machine for the transfer to said elevator of a hand composed line of matrices and spacebands, comprising means adapted to support matrices and spacebands by their ears during composition, manually operable line clamping means mounted independently of said supporting means, and means operable automatically by the application of the hand-stick to the assembler to release the matrices and spacebands from said supporting means.

5. A hand-stick comprising in combination a matrix supporting shelf, an adjustable line abutment, a normally fixed line abutment mounted for a limited inward movement to clamp the composed line, and a pair of closely spaced gripping members capable of being grasped by one hand, one of said members being fixed to the shelf and the other connected to the normally fixed abutment.

6. A hand stick comprising in combination a matrix supporting shelf, a pair of abutments between which the line is composed, one of said abutments having a limited inward movement from its normal position to clamp the composed line, and a pair of closely spaced gripping members capable of being grasped by one hand, one of said members being connected to the inwardly movable abutment, whereby the hand pressure exerted on said gripping members in manipulating the hand-stick will be transmitted to the movable abutment and thus utilized to clamp the composed line.

WILLIAM E. AYNGE. 50
